UNITED STATES PATENT OFFICE

155,623

DESIGN FOR A PLATE TYPE APPARATUS
FOR HANDLING FLUIDS

Benjamin G. Newhall, Little Falls, N. Y., assignor
to Cherry-Burrell Corporation, Wilmington,
Del., a corporation

Application February 24, 1947, Serial No. 137,102

Term of patent 14 years

(Cl. D81—21)

To all whom it may concern:

Be it known that I, Benjamin G. Newhall, a citizen of the United States, residing at Little Falls, in the county of Herkimer and State of New York, have invented a new, original, and ornamental Design for a Plate Type Apparatus for Handling Fluids, of which the following is a specification, reference being had to the accompanying drawing, forming part thereof.

In the drawing

Fig. 1 is a side elevational view of a plate type apparatus for handling fluids, showing my new design;

Fig. 2 is a right end elevation thereof;

Fig. 3 is a left end elevation thereof; and

Fig. 4 is a plan view thereof.

I claim:

The ornamental design for a plate type apparatus for handling fluids, substantially as shown.
BENJAMIN G. NEWHALL.
